(No Model.)

J. A. BALDWIN.

EXTENSION SCREEN.

No. 430,559.

Patented June 17, 1890.

UNITED STATES PATENT OFFICE.

JUDSON A. BALDWIN, OF WINOOSKI, ASSIGNOR TO THE QUEEN ANNE SCREEN COMPANY, OF BURLINGTON, VERMONT.

EXTENSION-SCREEN.

SPECIFICATION forming part of Letters Patent No. 430,559, dated June 17, 1890.

Application filed October 26, 1888. Serial No. 289,235. (No model.)

To all whom it may concern:

Be it known that I, JUDSON A. BALDWIN, a citizen of the United States, residing at Winooski, in the county of Chittenden and State 5 of Vermont, have invented certain new and useful Improvements in Extension-Screens, of which the following is a specification, reference being had therein to the accompanying drawings.

10 My invention relates to an improvement in extension window-screens; and it consists of panels or slides so attached at either end to pieces designed to slide in corresponding grooves in the outside edges of the horizontal bars of the screen-frame that the entire construction may be made of the cheapest material, in the simplest manner, and without affecting the ease and reliability of their lateral adjustment to the varying width of window-frames.

15 In the drawings, in which similar letters indicate like parts, Figure 1 is a horizontal section of my screen. Fig. 2 is an edge view of the same. Fig. 3 is a perspective of one of 25 the slides. Fig. 4 is a perspective of one corner of the screen. Fig. 5 is a side elevation of the screen complete. Fig. 6 is an end view of Fig. 5.

20 A is the screen-frame, which is designed to be covered with wire-netting, which is secured between the front and rear bars B B', which compose the top and bottom bars of the frame, and upon the end bars C C of the frame in the usual manner.

25 D D are end panels, which are intended to extend the width of the frame A at either end by being secured at their top and bottom extremities to the sliding pieces b b, which are provided with a tongue G on their interior or under edges, so as to readily slide horizontally in corresponding grooves I in the exterior edges of the front bars B of the frame. The pieces b b are of sufficient length to form a bearing to sustain the panels when drawn 45 out their full width. Their outward movement is limited by the strips d d, which are attached to the under side of the inner edges of the panels, and between the bars B B of the top and bottom bars coming in contact 50 with similar strips e e, secured to the corre-

sponding faces of the end bars C C. The closing movement of the panels is similarly limited by the interior extremities of the sliding pieces b b running against the intermediate pieces f f on the top and bottom bars 55 in the path of the bars b b. As the netting is secured between the front and rear bars B B' of the frame A, which is subsequently covered by the pieces which form the adjustable or sliding portion of the screen, a finished surface is presented on both sides of the frame when the screen is completed for use. By this simple arrangement of parts the screen can be readily constructed entirely of wood, which is the cheapest material to 60 use, without being susceptible to the objectionable influences of the weather to which it may be exposed, which in wooden screens of this character as otherwise made often prevents the sliding parts from moving easily or 65 at all on account of the shrinking or swelling of the wood. This desired result, as will be noticed, is accomplished by locating the sliding pieces b b on the outside instead of the inside edges of the bar B, care being had to 70 have but a single tenon, and this to be sufficiently narrower than the groove in which it slides to allow for extreme enlargement by dampness. The panels being then secured to these pieces their full width at the extremities of the grain of the wood, are never affected by the temperature, nor do they even 75 curl, so that they always slide easily. At the same time the attachment of the strip d, which forms the stop to their outward movement to nearly the entire length of the panel, 80 serves to give additional stiffness to the panel, thus materially preventing any tendency of the panels to side warping.

85 The tonguing and grooving of the sliding parts are quickly made by machinery, while the quantity of material required is as little as is possible to have.

90 The several parts are readily put together, and the screen when completed perfectly 95 meets the end desired in the simplest, cheapest, and reliable manner possible.

I claim—

90 The combination of a screen having top and bottom bars which are composed of front 100

and rear bars and end pieces, the stops secured to the end pieces, the front bars provided with longitudinal grooves, the panels provided with the tongued sliding pieces at 5 each end, which slide in the grooves made in the front bars, the strips secured to the inner edges of the panels, and the stop-strips secured to the top and bottom bars at or near their centers and in the path of the sliding

pieces, all combined to operate substantially as shown and described.

In testimony whereof I do affix my signature in presence of two witnesses.

JUDSON A. BALDWIN.
